UNITED STATES PATENT OFFICE.

ENOCH D. PARRISH, OF HARRISONVILLE, MISSOURI.

BED-RAIL FASTENER.

Application filed May 8, 1924. Serial No. 711,804.

To all whom it may concern:

Be it known that I, ENOCH D. PARRISH, a citizen of the United States of America, residing at Harrisonville, in the county of 5 Cass and State of Missouri, have invented certain new and useful Improvements in Bed-Rail Fasteners, of which the following is a specification.

This invention relates to new and useful 10 improvements in bed rail fasteners.

An important object of the invention is to provide a bed rail fastener which will permit the said rail to be reversed for adapting the same for supporting either slats or 15 spring mattresses.

A further object of the invention is to overcome the trouble and inconvenience of having to disconnect the bed rail by employing a hammer or other striking implement for disconnecting the same with the result that when the bed rail is knocked loose, it usually is entirely disconnected from the bed post carrying fastener and is permitted to fall to the floor.

25 Other objects and advantages of the invention will be apparent during the course of the following description.

In the accompanying drawing forming a part of this specification and in which like 30 numerals are employed for designating like parts throughout the same,

Figure 1 is a side elevational view of a bed rail shown in position for supporting slats and having the improved fastener carried thereby and arranged in operative position in respect to a bed post illustrated in dotted lines,

Figure 2 is a top plan view of Fig. 1.

40 Figure 3 is a transverse sectional view taken upon line III—III of Fig. 1.

Figure 4 is a detail elevational view and shows the bed rail arranged for supporting spring mattresses or the like,

45 Figure 5 is a detail elevational view of a portion of the fastener embodying this invention, and

Figure 6 is a top plan view of Fig. 5.

In the drawing, wherein for the purpose 50 of illustration is shown a preferred embodiment of this invention, the numeral 5 designates a bed post having the female fastener element 6 suitably connected thereto. This fastener element 6 is provided with a conventional form of tapered socket 7.

55 The numeral 8 designates a side rail which is formed from an angle iron and is adapt-

ed for having its end received in an angle socket 9 formed in a head 10. This bed rail is intended to be permanently connected to the head 10. A longitudinally extending bore 11 of square formation in cross-section is formed in this block 10 and is connected with the upper and lower faces 12 and 13 of the block by means of the longitudinally offset holes 14 and 15 which are arranged in the same longitudinal plane. The flat end wall 16 of this head 10 is formed with a vertically extending pocket 17 which crosses one end of the bore 11 and is of the same width as the said bore.

In Figs. 5 and 6 there is shown a tapered plug 18 which is formed integrally with a plate 19 having projecting from its opposite face an integrally formed stud 20 of square cross-sectional formation. This stud 20 is provided with a series of longitudinally spaced wells 21 which enter the said stud from the top face thereof.

The manner of connecting the reversible side rail 8 to the post 5 is as follows:

It will be apparent from Figs. 1 and 2 that the tapered plug 18 is adapted for being received within the tapered socket 7 formed in the fastener 6 carried by the post 5. This plug, due to its formation, will always position the stud 20 with the wells 21 entering the same from its top surface.

In Figs. 1 to 4 inclusive the side rail 8 with its head 10 are shown as being connected to the unitary structure illustrated in Figs. 5 and 6 by having the stud 20 positioned within the bore 11 of the head 10.

It will be apparent that the head 10 may be positioned upon the stud 20 either with the rail 8 arranged as shown in Figs. 1 to 3 inclusive for supporting slats or as shown in Fig. 4

90 for supporting spring mattresses. These four figures illustrate the reversibility of this side rail 8. By inspecting Fig. 1, it will be seen that the opening 15 formed in the head 10 will be arranged in axial alignment with the outer well 21 formed in the stud 20.

In Fig. 4, it will be seen that the opening 14 formed in the head 10 will be arranged in axial alignment with the inner well 21 of the stud 20.

The pin 22 is provided for being inserted in the alined opening and well for the purpose of retaining the head 10 positioned with the stud 20 residing within the bore 11. For the purpose of preventing this pin 22 from being lost, an eye portion 23 is formed in the head

thereof and is adapted to be connected to an eye 24 formed in the upper end of the tapered plug 18 by means of the chain 25. It will now be apparent that the side rail 8 5 may be rigidly connected to the post 5 by means of the various elements above referred to and that the rail 8 may be arranged for supporting either slats or spring mattresses.

10 It is to be understood that the form of this invention herewith shown and described is to be taken as a preferred example of the same, and that various changes in the shape, size, and arrangement of parts 15 may be resorted to without departing from the spirit of the invention or the scope of the subjoined claim.

Having thus described the invention, I claim:—

20 In a device of the type described, a post having a socketed fastener element carried thereby, a side rail, a head secured to said rail and having a longitudinally extending bore formed therein, longitudinally spaced

holes extending from opposite sides thereof inwardly to said bore, and a vertically extending pocket formed in the outer face thereof extending in the direction of the said holes, a tapered plug received in the socket of said fastener element, a plate received in the vertical pocket and formed integrally with said plug, a stud received in said bore and having a pair of spaced wells entering the same from one face thereof, said stud being integral with said plate, said wells being positioned in axial alignment with either one or the other of said holes in the head when the stud is received within said bore, a removable pin receivable in the aligned hole and well for retaining said stud in the bore of said head, and a section of chain connected to said tapered plug and removable pin for preventing the latter from becoming separated from the plug.

35 40 45 In testimony whereof I affix my signature.

ENOCH D. PARRISH.
